UNITED STATES PATENT OFFICE.

EDWARD J. FELLMAN, OF MILWAUKEE, WISCONSIN.

SEPARABLE HINGE.

1,261,914.

Specification of Letters Patent.

Patented Apr. 9, 1918.

Application filed July 21, 1917. Serial No. 182,013.

To all whom it may concern:

Be it known that I, EDWARD J. FELLMAN, a citizen of the United States, and resident of Milwaukee, in the county of Milwaukee and State of Wisconsin, have invented certain new and useful Improvements in Separable Hinges; and I do hereby declare that the following is a full, clear, and exact description thereof.

10 My invention relates to new and useful improvements in separable or loose joint hinges, particularly those adapted for use in connection with window screens, storm sashes, shutters and the like.

15 It is well known that separable hinges of the ordinary loose joint type are prone to rust very easily and quickly at the pins and in the knuckle joint and thereby render them unserviceable within a short time.

20 It is therefore primarily the object of the present invention to provide a loose joint hinge which is proof against rusting. This result is obtained by the peculiar, yet very simple nature of the parts forming the hinge.

25 It is also the object of this invention to provide means whereby various types, such as surface or mortise hinges, may be constructed from blanks of substantially the same shape. This is not possible with the usual shutter or window screen hinge.

Still another object of the present invention is to provide a hinge consisting of two parts which are reliably held against becoming accidentally separated.

30 With these general objects in view, the invention consists in the novel combination and arrangement of parts which will be hereinafter more particularly described and claimed.

40 In the accompanying drawings:—

Figure 1 represents a side elevational view of a half mortise hinge constructed in accordance with my invention, parts of said hinge being broken away and being shown in section.

Fig. 2 is a horizontal sectional view of a half mortise hinge taken on the plane of the line 2—2 of Fig. 1.

50 Fig. 3 is a similar view of a surface hinge. Fig. 4 is still another view similar to Fig. 2 illustrating a full mortise hinge, and

Figs. 5 and 6 are detail plan views of the blanks from which the two parts of my improved hinge are formed.

55 By reference to the several figures of the drawing, wherein similar reference charac-

ters indicate like parts throughout the several views, it will be seen that each hinge regardless of whether it is a surface or mortise type consists of three parts, a pintle carrying part 1, a ear carrying part 2, and a pintle 3. The first two parts are readily stamped from sheet metal of appropriate gage to form the blanks shown in Figs. 5 and 6.

60 The blank of the pintle carrying part 1 consists of an attaching portion 4 and a pair of laterally extending arms 5 and 6 which are spaced apart and have disposed therebetween a lip 7, the lower end of the latter being spaced from the arm 6 as at 8. The attaching portion 4 is provided with screw holes 9 to receive fastening screws 10.

65 The arms 5 and 6 are rolled upon themselves to form knuckles, the openings of which are aligned to receive said pintle 3. For convenience in description the knuckles will be designated by the same numerals as the above mentioned arms, that is to say, the knuckle formed from the arm 5 will bear 70 this numeral, while that constructed from the other arm will bear the numeral 6. These knuckles have a slight spring action and before application of the pintle are slightly smaller in diameter than the major portion 75 thereof. Said pintle will thereby be held tightly within the knuckles without additional fastening means other than the natural resiliency of the metal forming said knuckles.

80 The end of the pintle 3 which is normally disposed at the top when the same is positioned vertically projects slightly beyond the knuckle 5 as shown at 11. The intermediate portion of the pintle between the 85 knuckles 5 and 6 is reduced as at 12, said reduced portion extending from the inner end of the first mentioned knuckle to a point spaced from the inner end of the other knuckle.

85 As shown in Fig. 5 the blank for the ear carrying part of the hinge also has an attaching portion 13 provided with screw apertures 14. Connected with the attaching portion 13 by a contracted neck 15 is a 90 portion 16 on the opposite ends of which ears 17 and 18 are formed. The ears are constructed by bending this portion 16 laterally at its opposite ends. The ear 17, which is the upper ear, has a circular opening 19 95 for engagement with the preferably cylindrical end 11 of the pintle. The other ear

18 has an open end slot 20, the inner portion of which is substantially circular to thereby provide a contracted mouth 21. The circular portion of the slot 20 is designed for engagement with the cylindrical part of the pinte between the knuckles 5 and 6.

In assembling the two parts of the hinge thus formed the ear carrying part is so positioned that the slot in the ear 18 may engage the reduced portion 12 of the pinte with the other ear 17 positioned above the end 11 of said pinte.

Now upon downward movement of the ear carrying part, the ears carried thereby will be engaged with the cylindrical portions of the pinte. The mouth 21 of the slot is sufficiently wide to receive the reduced portion of the pinte, but is less than the width of the major portion thereof, whereby the two parts will be held in rotative relation when the ears are seated on the upper ends of the knuckles as shown in Fig. 1.

In order to hold the two parts against separation except when in one position, the stop lip 7 has been provided. This lip, as has been shown in the several figures will engage the ear 18 except when the mouth of the slot 20 is alined therewith. In other words, the sliding movement of the ear 18 will be limited by the knuckles 6 adjacent the end of said lip except when in separating position.

From Fig. 1 it will be noted that the ear 17 will effectively cover the knuckle 5 and form in effect a cover therefor to prevent rusting of the several parts, particularly said knuckles. This protection will be afforded even though the opening 19 is somewhat larger than the end 11 of the pinte which is necessary to allow the screen and window frame, or other parts on which the hinge is to be used, to move together and to compensate for any slight inaccuracies in the positioning of the parts of the hinge.

Figs. 2, 3 and 4 show four positions into which the two blanks 1 and 2 may be bent to construct hinges for different purposes. Fig. 2 shows two positions of a half mortise hinge, one position being indicated in dot and dash lines. The other two figures illustrate surface and full mortise hinges respectively.

I claim:

1. A two part separable hinge including spaced knuckles, a pinte carried by said knuckles, a stop spaced from one of said

knuckles, and an ear rotatable on the pinte between said stop and the adjacent knuckle, said ear having a slot adapted to be alined with said stop to permit longitudinal sliding movement of the ear on the pinte.

2. A two-part separable hinge including a pair of spaced knuckles, a pinte connecting the knuckles, one portion of said pinte being reduced in cross section, and an ear adapted to rotate on the larger portion of said pinte and having a slot, the mouth of the same being contracted to substantially the width of the reduced portion of said pinte, said ear being disposed on the pinte by the engagement of the mouth of the slot with the reduced portion thereof, said slot being movable out of engagement with the reduced portion to prevent separation of said ear and pinte.

3. A two-part separable hinge including a pair of spaced knuckles, a pinte connecting the knuckles, one portion of said pinte being reduced in cross section, an ear adapted to rotate on the larger portion of said pinte and having a slot, the mouth of the same being contracted to substantially the width of the reduced portion of said pinte, and a stop disposed between said knuckles to normally limit longitudinal sliding movement of the ear on the pinte, said ear being disposed on the pinte by the engagement of the slot with the reduced portion thereof when said mouth is alined with the stop.

4. A two part separable hinge, one part including a pair of spaced knuckles, a pinte disposed in said knuckles, one end projecting beyond one of the knuckles, the intermediate portion being reduced in cross section, a stop lip disposed between the knuckles and spaced from one, and the other part comprising a pair of spaced ears, one having an aperture to receive the projecting end of the pinte, the other ear having a slot to receive the portion of the pinte between said knuckles, the mouth of said slot being contracted to substantially the width of the reduced portion of the pinte, whereby said ear is disposed on said pinte by the engagement of the mouth of the slot and the reduced portion thereof when said mouth is alined with said stop lip.

In testimony that I claim the foregoing I have hereunto set my hand at Milwaukee, in the county of Milwaukee and State of Wisconsin.

EDWARD J. FELLMAN.
